ELECTRON MICROSCOPE

Bodo von Borries and Ernst Ruska, Berlin-Spandau, Germany, assignors to Fides Gesellschaft für die Verwaltung und Verwertung von gewerblichen Schutzrechten mit beschränkter Haftung, Berlin, Germany, a corporation of Germany

Application August 17, 1938, Serial No. 225,278
In Germany August 17, 1937

6 Claims. (Cl. 250—49.5)

This invention relates to electron microscopes and consists in means for adjusting the object very exactly with respect to the objective.

According to the invention, the discharge vessel of an electron microscope is subdivided in the neighborhood of the object, and the two parts of the vessel are displaceable relative to each other and at right angles to the axis of the electron beam, roller-shaped bodies being provided to absorb the forces created between these parts by the vacuum. It is thus possible to adjust very accurately the part carrying the object with respect to that carrying the objective, since the roller-shaped pressure bodies only negligibly hinder a displacement of the two movable parts with respect to one another. This displacement will also not be affected if the object is intensely cooled (for instance, with liquid air), since between the two opposite surfaces lying directly upon each other no grease film is interposed which would solidify at the low temperature.

A practical embodiment of the invention is illustrated in the accompanying drawing in semi-diagrammatic form, in which—

Fig. 1 represents a central sectional elevation of the portion of the microscope embodying the invention.

Fig. 2 represents a plan view of Fig. 1.

Fig. 3 represents in sectional elevation the adjusting screw 16 and its support, and

Fig. 4 represents a bottom view of sluice 1 in Fig. 1.

Referring to Fig. 1, 1 designates the object-carrying member of an electron microscope. The central bore 1' of this member forms part of the evacuated discharge vessel of the microscope and is arranged so as to form a passage for the beam of electron rays which issue from a cathode (not illustrated) in the direction of the arrow 10. The member 1 is designed as a sluice in order to permit the insertion of objects into the path of the electron rays while the interior of the microscope remains evacuated. To this end, the member 1 has a transverse bore 2 for the reception of a plug or cock into the lateral bore of which the object may be inserted and which allows bringing the object to point 3. This plug structure is not shown here, as its construction does not form part of the present invention proper. A suitable sluice is illustrated and described in the copending application of Heinz Otto Müller, Serial No. 225,915.

The second relatively movable part or member of the electron microscope comprises a magnetic lens system for electron-optically biasing the

electron beam. The upper surface of this second member is formed by a plate which forms part of the ferromagnetic enclosure of a magnet coil 6 and abuts against the vacuum-tight tubular wall portion 5 of the discharge vessel, this wall portion being non-magnetic. The pole pieces 7 and 8 of the magnetic lens are threaded into the tubular wall portion 5. 9 represents a cooling chamber for cooling the coil 6, and 9' a nipple for supplying the cooling fluid.

The beam of electron rays after having passed through member 1 and through the object located at point 3, passes through the central apertures of the pole pieces 7 and 8 and thence directly or after being subjected to a further electron-optical bias, onto a surface or electrode so as to produce an enlarged image of the object. The other parts of the microscope are of common and well-known type, and, for the sake of clearness, are omitted in the drawing.

Several, preferably three, pressure sustaining bodies are arranged between the sluice carrier 1 and the plate 4. In the embodiment shown steel balls 11 are employed for this purpose which are mounted at both sides on polished steel or agate plates 12 and 13. The diameter of these pressure bodies is so chosen that the ground surface of member 1 does not directly rest on the plate 4. In this manner a sliding friction is prevented between these parts. To seal the gap between the sluice carrier 1 and the plate 4 the flanged rubber cuff 14 is provided which is secured to the carrier with the aid of binding wire and to the plate 4 by means of a flange 15. Since the lateral adjustments of sluice carrier 1 are only very slight, the yield of cuff 14 is sufficient to permit this. The sluice carrier with its object 3 is adjusted with respect to the magnetic lens 7, 8 by means of the screws 16, 17 and 18 spaced 120° from one another as shown in Fig. 2, each being threaded into a bracket forming part of plate 15. The screw 18 is brought into engagement with the sluice carrier 1 with the aid of a resilient member 19 so as to permit slight adjustments of screws 16 and 17 without backing up or advancing screw 18. The pressure screws 16 and 17, which engage the sluice carrier directly, are as shown in Fig. 3 preferably provided with a steel ball 20 at their ends which bears against a small agate plate 21 set into the sluice carrier 1 as shown in detail in Fig. 3.

In order to improve the communication between the two vacuum chambers lying at both sides of the object the sluice carrier 1 is pro-

vided with several bores 22, 23 and 24. The bores 25 arranged in the magnet system serve the same purpose. A direct communication between the space lying above the object sluice and the space below the lens system may also be established by a conduit forming a by-pass. To avoid in such an arrangement that the equalization of the vacuum pressure produces additional forces which may change the position of the object, it is necessary that two or more of the above-mentioned ducts be arranged symmetrically to the axis of the discharge device.

In order to cool the object a cooling duct 26 having the form shown in Fig. 4 and which partly surrounds the bore 24 is provided in the sluice carrier 1. The cooling duct is preferably produced in such a manner that first a groove of suitable form is milled into the lower face of the sluice which is then closed by a plate 27 soldered thereto. The ends of the cooling duct 26 are provided with nipples, such as nipple 26' shown in Fig. 1, to be connected with fluid supply conduits.

Electron microscopes according to the invention allow very fine adjustments of the object relative to the electron-optical axis of the electron beam in any direction transverse to this axis.

What is claimed is:

1. In an electron-optical device having means for holding an object and lens means for electron-optically producing an image of said object, in combination, a vacuum vessel having a vessel portion for accommodating said holding means with part of said holding means disposed exteriorly of said vessel, and another vessel portion containing said lens means with part of said lens means disposed exteriorly of said vessel, said vessel being subdivided transversely with respect to the electron-optical axis and between said two vessel portions, and said vessel portions being transversely movable relative to each other, and mechanical adjusting means connected between said exteriorly disposed parts of said vessel portions for changing and fixing the relative position of said vessel portions.

2. In a microscopic device having means for holding an object in the path of a corpuscular beam, and lens means for electron-optically biasing said beam, in combination, a vacuum vessel having two adjoining vessel portions movable relative to each other along a plane transverse to said beam path, one of said vessel portions being designed for accommodating said object-holding means and said other vessel portion being firmly connected with said lens means, a cuff of yielding material arranged concentrically to said path and connected with said two vessel portions to provide a gas-tight seal, antifriction means arranged between said portions and within said cuff, and means for adjusting said por-

tions relative to each other in any direction of said plane.

3. In a microscopic device having means for holding an object in the path of a corpuscular beam, and lens means for electron-optically biasing said beam, in combination, a vacuum vessel subdivided so as to form two vessel portions, the plane of division extending close to the object and transversely with respect to said beam path, said two vessel portions being movable relative to each other in different directions along said plane of division, gas-tight sealing means of yielding type disposed at the junction of said vessel portions, three adjusting screw means spaced circumferentially and mounted on one of said vessel portions so as to bear against said other vessel portion, one of said screw means including a bearing yielding towards the two other adjusting means.

4. In a microscopic device having means for holding an object in the path of a corpuscular beam, and lens means for electron-optically biasing said beam, in combination, a vacuum vessel having two adjoining vessel portions movable relative to each other along a plane transverse to said beam path, one of said vessel portions forming the stationary member of a cock-type sluicing device for receiving said object-holding means, and said other vessel portion being associated with said lens means, said two vessel portions having coaxial central bores, respectively, forming a passage for said beam and communicating lateral by-pass ducts for equalizing pressure differences, antifriction means disposed between said vessel portions, and means for adjusting said portions relative to each other in any direction along said transverse plane.

5. In a microscope having a vacuum vessel, means in said vessel for exposing an object to a corpuscular beam and lens means for biasing said beam, in combination, a sluicing device for receiving said object, said sluicing device comprising a body forming a portion of said vacuum vessel and being displaceable relative to the other vessel portions, said body having an axial bore forming a passage for said beam, a lateral by-pass duct and a cooling duct, said axial bore and said by-pass duct communicating with the vacuum in said other vessel portions, and said cooling duct separated from said vacuum and arranged so as to substantially surround said axial bore close to the place of said object, and means for passing cooling agent from the outside of said vessel through said cooling duct.

6. An apparatus as set forth in claim 1, wherein antifriction means and resilient tightening means are disposed between said two vessel portions.
